UNITED STATES PATENT OFFICE.

FANNIE BROWN, OF CLEVELAND, OHIO.

MANICURE DEVICE.

Application filed November 23, 1925. Serial No. 70,806.

This invention relates to manicure devices and has for its object the provision of a new, improved, inexpensive and sanitary nail buffer; the provision of a device of this character designed especially for the use of commercial manicurists whereby the spread of infection may be prevented and a feeling of safety inspired in patrons, without detracting from the satisfactory nature of the work done; the provision of a new and cheapened exchangeable polishing element for such devices; while further objects and advantages of the invention will become apparent as the description proceeds.

In the drawings accompanying and forming a part of this application, Fig. 1 is a side elevation partly in section of a nail buffer embodying my improvements; Fig. 2 is a cross sectional view corresponding to the line 3—3 of Fig. 1; and Fig. 3 is a side elevation also partly in section of one of the exchangeable polishing elements employed herewith.

This device comprises the usual oblong back 1 often made of wood, though sometimes of celluloid or other synthetic material, having on one side a handle 2 and upon the opposite side the buffer body which here comprises a solid block 3 of proper size and shape rigidly with the back 1 and surmounted by a padding 4 generally of felt or like material. The polishing element 5 is positioned over and around this body part and consists of one or more thicknesses of soft, porous, paper impregnated with powder of the type and color desired for the purpose and shaped in advance to conform to the body part. This element is preferably secured in place by means of a flexible sheet metal band 6 which snugly surrounds the marginal portion of such paper element, thus overlying the portion 3. The exterior of this portion is preferably made slightly tapering at all points as illustrated at 7 in Figs. 1 and 2 and the padding 4 preferably conforms to the same taper, thus facilitating the forming of the paper polishing elements and enabling them to be gripped tightly without wrinkling when the band 6 is applied. In case a fairly tough, porous, crinkled paper is employed it will ordinarily

last through a single complete manicuring operation. Being cheap and easily applied these elements can be discarded without hesitation; also by reason of their cheapness it is possible to keep on hand a large number of elements impregnated with different shades or degrees of powder or with different medicaments without undue investment. This enables each patron to be afforded the satisfaction of feeling that he is being safeguarded in his health as well as being humored in his desires. Other advantages of making the paper elements tapered are that they can be nested together for shipment and storage, and that they can be employed two or more layers deep on the buffer if desired, thereby varying the hardness of the buffer according to the desires of different patrons.

Having thus described my invention what I claim is:

1. A nail buffer comprising a hard body portion, a soft body portion, an exchangeable polishing element surrounding said soft portion and lapping over onto said hard body portion and conforming to both portions, and means securing said element to said hard portion whereby it is held in place, said element consisting of soft, porous paper impregnated with powder.

2. A polishing element for nail buffers consisting of a hollow dish-shaped member of soft, porous paper impregnated with powder and shaped to conform to the body of a buffer.

3. A nail buffer comprising a body portion having a solid base part and a soft overlying part, said base part tapering on all sides gradually toward said overlying part and the overlying part being also tapered in the same direction, an exchangeable polishing element consisting of soft, porous paper preshaped to surround and conform to said body portion, and a flat, flexible, sheet metal band surrounding that portion of said element which overlies the solid base part and gripping the same thereto.

In testimony whereof I hereunto affix my signature.

FANNIE BROWN.
